UNITED STATES PATENT OFFICE.

JOHN L. HIGHBARGER, OF SHARPSBURG, MARYLAND.

SAW JOINTING AND SETTING DEVICE.

SPECIFICATION forming part of Letters Patent No. 317,784, dated May 12, 1885.

Application filed January 13, 1885. (No model.)

To all whom it may concern:

Be it known that I, JOHN L. HIGHBARGER, a citizen of the United States, residing at Sharpsburg, in the county of Washington and State of Maryland, have invented certain new and useful Improvements in a Combined File, Facer, and Saw-Set; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a vertical cross-sectional view of my device. Fig. 2 is a side view of the same. Fig. 3 is a top view, and Fig. 4 is a perspective view, of the file.

This invention relates to means for jointing and setting saws; and it consists in the construction and novel arrangement of devices, as hereinafter set forth, and pointed out in the appended claims.

In the accompanying drawings, the letter A designates the sectional holder, composed of the lateral parts B B. Each of these sections is formed with a longitudinal transverse groove, c, which, when the sections are placed together, forms with the groove in the opposite section the seat for the file. The grooves c c, forming the file-seat, are laterally extended, so that the seat will be wider than the file D, and there will be room therein to adjust the file from side to side, so that its serrated surface can be wholly utilized. The sections B B approximate at their inner faces, E E, and they are held together by the adjustable connection—the strap—which is secured to one of the sections and extends over the other, and is attached thereto by means of a clamp-screw, G, which passes through a slot, H, of said strap. The projecting portion of this connecting-strap fits in a transverse recess, K, of the opposite section, so that the connection is made strong and solid.

The saw is admitted between the interior faces, E E, to the file, and at the inner ends of

these faces next the file-grooves they are beveled or turned obliquely outward a little to form angular offset faces m, which correspond to the angle at which the teeth are set on each side of the plane of the saw.

To assist in setting the teeth, the file is formed with a setting-notch in its end, said notch being bounded on one side by the short vertical wall v, and on the other side by a still shorter vertical wall, z, adjacent to the long oblique wall w, which latter wall determines the extent of the angle or set. In order that the tooth t may readily operate upon the tooth of a saw without interfering with the adjacent tooth it is somewhat beveled on each side.

The outer sides of the holder are beveled at s, so that said holder can be easily grasped in the hand and allow the fingers to move on the blade of the saw to assist in guiding the holder. The saw being held in a vise the facer is moved back and forth upon its edge and squares the teeth.

Having described this invention, what I claim, and desire to secure by Letters Patent, is—

1. The saw jointer and set consisting of the file-holding sections adjustably connected together and provided with file-grooves made wider than the file to facilitate adjustment of the latter, the beveled offsets m m of the adjacent faces E, and the file having a setting-notch in its end formed with an oblique regulating wall and a short beveled wall, substantially as specified.

2. A saw-setting file having in one end a notch formed by a short vertical wall, v, and an opposite shorter vertical wall, z, terminating in a tooth, t, and the wall v terminating in an oblique wall, w, adapted to serve in connection with the holder, substantially as set forth.

In testimony whereof I affix my signature in presence of two witnesses.

JOHN L. HIGHBARGER.
